AGITATOR FOR A LAUNDRY MACHINE

William Ohmann, Benton Harbor, Mich., assignor to
Whirlpool Corporation, a corporation of Delaware

Filed Jan. 9, 1963, Ser. No. 73,114

Term of patent 14 years

(Cl. D49—1)

The side not shown is substantially the same as the side shown.

I claim:

The ornamental design for an agitator for a laundry machine, as shown and described.
